UNITED STATES PATENT OFFICE.

JULIUS KOPIETZ, OF DETROIT, MICHIGAN.

KEY-EXTRACTOR.

977,018.

Specification of Letters Patent. Patented Nov. 29, 1910.

Application filed December 22, 1909. Serial No. 534,446.

To all whom it may concern:

Be it known that I, JULIUS KOPIETZ, a citizen of the United States of America, residing at Detroit, in the county of Wayne and State of Michigan, have invented certain new and useful Improvements in Key-Extractors, of which the following is a specification, reference being had therein to the accompanying drawings.

10 This invention relates to a device for extracting keys for holding pulleys, wheels and other devices upon shafts, and its object is to provide a simple and convenient tool which may be readily engaged with a key in a shaft and is so arranged and constructed as to give ample power for the purpose.

15 A further object is to provide a tool adapted to engage the various sizes and forms of keys and which has the several advantages of the particular construction and arrangement of parts, all as hereinafter more fully described reference being had to the accompanying drawing, in which,

Figure 1 is a perspective view of a device 25 embodying the invention; Fig. 2 is a longitudinal section of the device showing the same applied to a key holding a pulley upon a shaft; Fig. 3 is a sectional detail showing the device as applied to another form of 30 key; and Fig. 4 is an elevation of the disk or head.

As shown in the drawings 1 represents a frame of suitable shape and size within which a second open frame or carrier 2 is mounted to slide by providing slots 3 in the 35 side members of the main frame engaged by pins 4 on the sides of the carrier 2. Mounted within the carrier 2 upon the rear end or cross wall 5 thereof is a circular disk or head 6 secured to the inner face of the wall by means of a stud bolt 7, said bolt being provided with a reduced and screwthreaded end to engage a screwthreaded opening in the wall and forming a shoulder 8 to engage the 40 wall so that the disk 6 will turn freely upon the bolt between the face of the wall and the head of the bolt.

The disk or head 6 is provided with a series of notches 9 in its periphery, said 50 notches being of different sizes to fit the various sizes of keys, one of such keys being illustrated at 10 in Fig. 2, as applied to a grooved shaft 11 and securing a pulley 12 in place thereon. To the forward end or wall 13 of the carrier 2 is attached a screw shaft 14 by reducing one end of the shaft

slightly to engage a bearing in the wall and further reducing and screw threading the extreme end of the shaft to receive a nut 15 to engage the shoulder 16 formed by said 60 reduced end and hold the shaft in its bearing in the wall in a manner to permit the same to turn freely therein. The shaft 14 is screw-threaded throughout its length and extends outward through the screwthreaded opening 65 in the outer end 17 of the frame 1. The outer end 18 of the shaft 14 is squared to receive a wrench for turning the shaft and is also provided with a transverse opening to receive a bar 19 slidable therein for turning 70 the shaft.

As shown in Fig. 2, the tool is applied to the work by engaging one of the notches in the head 6 with the shank of the key to be extracted and with the head engaging the 75 inner side of the head of the key, and the inner end 20 of the frame 1 engaging the end of the hub of the pulley. After being placed in this position the shaft 14 is turned to draw the carrier 2 toward the outer end 80 17 of the frame 1 thus bringing the head 6 into engagement with the head of the key and causing the key to be drawn from its seat.

The head or disk 6 may, if desired, be 85 provided with holes 21 in its periphery between the notches 9 and within these holes may be secured one or more short pins 22 which may be employed as shown in Fig. 3, to extract the key having no head, by drilling 90 a hole in the key to receive the pin.

The device may be quickly and easily applied to any key in any position and the screw shaft affords ample power for extracting any key of a size ordinarily used in 95 securing the common sizes of pulleys to shafting.

Having thus fully described my invention what I claim is:—

1. A device of the character described 100 comprising a supporting frame, a carrier movable upon said frame, a rotatable head on said carrier having a series of notches of varying sizes adapted to engage keys, and means for moving the carrier longitudinally 105 of the frame.

2. A device of the character described comprising an open supporting frame having sides and ends, an open carrier frame within the supporting frame slidable longitudinally thereof, a rotatable head having a 110 series of notches of various sizes adapted to

engage keys and pivotally attached to one end of the carrier, and a screw shaft attached at one end to the other end of the carrier and extending through the screw-threaded opening in the end of the supporting frame.

3. A device of the character described comprising a supporting frame having sides provided with longitudinal slots and a screw threaded opening in one end, an open carrier having end walls and adapted to slide within the supporting frame, means on the carrier engaging the slots in the sides of the

frame, a rotatable head having a series of notches of varying sizes adapted to engage 15 keys and pivotally secured within the carrier to one of the end walls thereof, and a screw shaft engaging the screwthreaded opening in the frame and attached at its inner end to the other end wall of the carrier. 20

In testimony whereof I affix my signature in presence of two witnesses.

JULIUS KOPIETZ.
